Primary Examiner — Michael A. Pratt

(57) **CLAIM**

The ornamental design for beverage bottle, as shown and described.

DESCRIPTION

1.-2. Beverage bottle

1.1 : Front

1.2 : Top

1.3 : Bottom

1.4 : Perspective

1.5 : Reference

1.6 : Cross sectional

2.1 : Front

2.2 : Top

2.3 : Bottom

2.4 : Perspective

2.5 : Reference

2.6 : Cross sectional

The back view, the right view and the left view are omitted since they are same as the front view, respectively; reproductions 1.5 and 2.5 are reference views which include the broken lines showing a three-dimensional shape of the article surface and do not form part of the claimed designs; reproductions 1.6 and 2.6 are cross-sectional views sectioned vertically at the center part of the front views.
